(57) **CLAIM**

The ornamental design for a network device housing, as shown and described.

DESCRIPTION

FIG. 1 is a first perspective view of an embodiment of a network device housing including at least one ventilation opening.

FIG. 2 is a second perspective view thereof.

FIG. 3 is a third perspective view thereof, with a cover part spaced apart from the housing.

FIG. 4 is a top view thereof.

FIG. 5 is a bottom view thereof.

FIG. 6 is a front view thereof.

FIG. 7 is a back view thereof, with the left side and right side views being generally identical thereto; and,

FIG. 8 is a cross-sectional view thereof taken substantially along lines 8—8 of FIG. 4.

The broken line(s) showing the ventilation openings or holes are for the purpose of illustrating unclaimed portions. The broken lines showing the article cut away are for the purpose of indicating that no specific height is claimed.
